UNITED STATES PATENT OFFICE.

WESLEY J. JOHNSON, OF CHICAGO, ILLINOIS.

DUPLEX GRATING FOR PIPELESS FURNACES.

1,394,260.

Specification of Letters Patent.

Patented Oct. 18, 1921.

Application filed March 27, 1919. Serial No. 285,514.

To all whom it may concern:

Be it known that I, WESLEY J. JOHNSON, a citizen of the United States, residing at Chicago, in the county of Cook and State 5 of Illinois, have invented certain new and useful Improvements in Duplex Gratings for Pipeless Furnaces, of which the following is the specification.

This invention relates to pipeless furnaces and more particularly to the grating 10 adapted to be positioned in the floor or other suitable place to permit the hot air to enter the room from the furnace, and the cooler or cold air to pass from the room through a 15 portion of the grating back to the furnace to be reheated.

In the conventional type of duplex grating for pipeless furnaces, the upper end or opening of the pipe conducting the hot air 20 from the furnace to the room is positioned centrally of the grating frame and has an equal space on all sides thereof, covered with grating through which the cold air passes on its way back to the furnace to be again heated 25 before being returned to the room through the hot air pipe. Since the upper portion of the framework or offset surrounding the furnace doors (to allow the necessary radius for the outer casing), and connecting the 30 inner casing with the outer casing, forms an obstructing shelf or barrier opposing the passage of the cold air returning from the room to the furnace at this particular part of the cold air space, it will be seen that the 35 returning cold air cannot pass directly down at this side of the furnace, but must be deflected sidewise to clear said shelf or barrier and then mingle with the cold air at the sides of the furnace. This conventional type 40 is therefore objectionable for many reasons, among which may be mentioned the loss of efficiency of the furnace, due to the inability of all of the cold air to pass freely and directly down to the lower part of the furnace; 45 the inability of workmen to locate the grating well up in the corner of a room or closely alongside a wall when a wall or other obstruction is encountered in the basement, and prevent setting the furnace in exactly 50 the spot desired; the inability of the occupants of the house to comfortably use the duplex grating as a foot warmer, due to the presence of downwardly passing currents of cold air on all exterior sides of the hot air

pipe; as well as other objections not specifically mentioned. All of these objections and others are entirely obviated in my improved grating, in which I so place the hot air pipe with relation to the exterior cold air grating that the circumference of the former substantially contacts with the marginal portion of the latter on that side of the grating adjacent the said obstructing shelf or barrier above the fire door.

Among the objects of my invention, therefore, is to provide a duplex grating of such form as to greatly increase the efficiency of the furnace by causing the returning cold air to pass directly to those parts of the furnace best capable of effectively handling the same for quick reheating; further to provide such grating that workmen may readily place the furnace in position to bring the grating into corners or other desirable places difficult to reach with the old form of grating; further, to make possible the comfortable warming of one's feet over the hot air pipe without encountering currents of cold air; further, to increase the amount of air delivered to the apparatus; further, to provide a duplex grating of maximum simplicity, economy, and efficaciousness; and such further objects, advantages, and capabilities as will later more fully appear.

My invention further resides in the combination, construction, and arrangement of parts illustrated in the accompanying drawing, and, while I have shown therein a preferred embodiment, I desire the same to be understood as illustrative only, and susceptible of modification and change without departing from the spirit of my invention.

In the drawings:

Figure 1 is vertical longitudinal section through a central plane of a furnace equipped with my improved grating and showing in dotted lines the imaginary position that would be occupied by the old conventional type of grating and connections.

Fig. 2 is a perspective view of the exterior of a pipeless furnace showing the obstruction to the downwardly passing cold air at the front of the furnace.

Fig. 3 is a plan view of my improved grating, the dotted lines showing the imaginary position of the exterior frame of the old conventional type with relation to the grating of the hot air pipe.

Fig. 4 is a sectional view of Fig. 3, taken through the center of the grating, for the hot air pipe.

Referring more in detail to the drawing, 5 A designates generally a pipeless furnace comprising the outer casing 1, the inner casing 2, spaced therefrom, (between which casings is the cold air passage 3), the fire pot 4 (having the customary fire-grate 5, combustion chamber 6 and smoke flue 7), and the usual frame work 8 surrounding the fire door 9, the clean out and draft check door 10, and ash door 11, the upper part 10 of which frame work is designated by 12. 15 This frame work, as will be understood, affords proper radius for the outer casing without obstructing the fire, cleanout, and ash doors.

My improved grating is designated at 13, 20 and comprises two main sections, to wit, the inner section 14 for the hot air pipe 15, and the outer section 16 for the cold air space or passage 3; the hot air pipe being flared as shown at 17 to compensate for the 25 difference in diameter between its top and the inner casing of the furnace. As shown in Fig. 3, the inner section 14 of the grating is preferably round (although other shapes may obviously be availed of) and is positioned with one side substantially in contact with the marginal portion of the outer section 16, whereby to practically eliminate the cold air grating at that portion of my grating falling nearest to the top plate 12 30 of the frame work 8 spacing the outer casing from the inner casing. The very small amount of grating space (if any) existing at this front edge of the cold air grating is so small as to be practically negligible. 35 The result of this structure is that the cold air returning to the furnace through the cold air grating will be substantially all forced to pass through those parts of the grating lying at the two sides and rear of the hot air pipe and thus carried directly to 40 those parts of the furnace best able to handle it, that is, through those parts of the cold air space 3, unobstructed by the top plate 12 over the furnace doors. It will thus be 45 seen that the large volume of cold air carried directly against the top plate 12 in the old conventional type of grating is eliminated, and substantially all of the cold air thrown directly into those passages able to 50 handle it with the greatest efficiency. This will add approximately 25% more air delivered to the apparatus, and thus greatly increase its capacity.

The grating may obviously be formed in 55 many ways, such as by casting it with the cold air outer section and marginal frame all in one piece, provided with an opening and appropriate flange within which the inner section 14 rests, the inner section also 60 being cast in one piece, as shown in Figs. 65

3 and 4; or the grating may be built up of separate bars of steel or other material secured in an outer frame, also of the form of Fig. 3; or if desired, the entire grating may be made integral and rest upon the 70 top of the hot air pipe, with which latter it has appropriate connection by means of a flange piece 20, as shown in Fig. 1.

As is readily seen in Fig. 1, the bulk of the 75 cold is thrown to the rear of the furnace, the remainder being substantially all thrown to the sides, which parts obviously through the medium of the space 3 conducts it directly downward to the bottom of the inner casing and up in contact with the fire bowl. 80 As will be understood from the dotted line in Fig. 1, (which represent the location of the grating and connection with the old conventional type of grating), my new type of 85 grating enables the workman to more readily locate it in corners, even though protruding walls or the like be encountered in the basement. This enables the proper placing of the grating with relation to partition walls and corners. Also, due to the absence of 90 the downwardly passing currents of cold air at the front edge of my grating, one can use the warm air portion as a foot warmer without discomfort or danger from drafts. 95

From the above it will be seen that I have produced a form of grating that eliminates 100 all of the objections of the old conventional type, one which is cheap to manufacture, simple in construction, possesses maximum efficiency, increases the capacity of the furnace, and one which greatly enlarges the field of possibilities of the pipeless furnace.

Having now described my invention, I claim:

1. A duplex grating, for use with pipeless 105 furnaces having a warm air jacket and a cold air jacket substantially surrounding said first named jacket at its emergent end, comprising a cold air section and a warm air section, said sections adapted to cover the 110 open ends of the cold and warm air jackets respectively, the warm air section being positioned adjacent one side of but within the cold air section, whereby to cause the cold air to substantially all pass directly to the 115 heating portions of the furnace for immediate heating.

2. A duplex grating for use with pipeless 120 furnaces having a warm air jacket and a cold air jacket substantially surrounding the same at its emergent end, comprising a cold air section having a marginal portion, and a warm air section lying within said cold air section and substantially touching said marginal portion on one side of the grating, 125 the warm air section being entirely surrounded by the cold air section except at said touching point, whereby to cause the cold air to pass downwardly outside of the hot air section on all sides except at the said 130

touching side to prevent passage of cold air to non-heating portions of the furnace.

3. In combination, a hot air passage for conducting heated air from a heat generating means to a room, a cold air passage for conducting cold air from the room to said means and lying outside of said hot air passage, and a common grating over said passages, said hot air passage being so joined 5 with the grating with relation to the cold air passage that substantially no cold air will be permitted to pass down at the front, but will be permitted to pass down freely on all other sides to partially surround the 10 heat generating means.

4. In combination, a hot air passage, a cold air passage, a common grating over said passages, the hot air passage being joined with the grating at one side thereof whereby 15 to cause the cold air substantially all to pass down the cold air passage at the sides and back, and to throw the bulk of the grating toward the rear of the hot air passage to

facilitate placing the grating in the corners of rooms and in convenient position with 25 relation to partitions and walls.

5. A duplex grating, for use with pipeless furnaces having a warm air jacket and a cold air jacket partially surrounding the warm air jacket from the emergent end to 30 the heating portion of the furnace, comprising an openwork warm air section and an openwork cold air section adapted to cover the open ends of the warm and cold air jackets respectively, the warm air section 35 being positioned to one side of the cold air section and with one of its sides substantially touching one of the marginal side portions of the grating, so that the cold air will be substantially excluded from passing 40 downwardly along said touching side of the warm air section, to non-heating portions of the furnace.

In witness whereof, I hereunto subscribe my name to this specification.

WESLEY J. JOHNSON.
